UNITED STATES PATENT OFFICE.

LEWIS R. TOMPKINS, OF ATLANTIC CITY, NEW JERSEY, ASSIGNOR OF ONE-HALF TO
GEORGE H. SHEA, OF QUARRYVILLE, PENNSYLVANIA.

CLOSURE MEMBER.

Application filed February 20, 1925. Serial No. 10,698.

This invention relates to closure members, and more particularly to means for normally closing the opening surrounding the pole in a fire engine house.

In the usual arrangement of fire engine houses, the apparatus is stored on the first floor and sleeping quarters for the firemen are provided on the second floor above the room in which the fire apparatus is stored. The second floor is provided with an opening and a pole is arranged in this opening down which the firemen slide when an alarm is sounded, thus saving time in responding to an alarm. This opening in the floor is unsatisfactory and unsafe, as it permits drafts and fumes to enter the sleeping quarters and is also dangerous in that a person unacquainted with the arrangement may fall through it.

An object of the present invention is to provide a motor operated closure member which is normally maintained in closed position, together with means controlled by the sounding of an alarm for opening said member.

A further object is to provide an apparatus of this character which will remain open for a given period and automatically close.

In the accompanying drawings, I have shown one embodiment of the invention. In this showing:

Figure 1 is a perspective view of the ceiling of the first floor of a fire engine house showing the invention installed,

Figure 2 is a bottom plan view,

Figure 3 is a diagrammatic view of the electric circuits,

Figure 4 is a plan view of the casing in which the apparatus or mechanism is mounted, with the cover removed,

Figure 5 is a perspective view of a portion of the apparatus removed from the casing,

Figure 6 is a vertical sectional view on line 6—6 of Figure 4,

Figure 7 is a sectional view on line 7—7 of Figure 2,

Figure 8 is a similar view on line 8—8 of Figure 7,

Figure 9 is a vertical sectional view on line 9—9 of Figure 4,

Figure 10 is a vertical sectional view on line 10—10 of Figure 9,

Figure 11 is a perspective view of a control lever or trip mechanism,

Figure 12 is a vertical sectional view on line 12—12 of Figure 4, and,

Figure 13 is a perspective view of a yoke by means of which the actuation of the closure member is controlled.

Referring to the drawings, the reference numeral 1 designates a box or casing which is adapted to be arranged beneath the ceiling adjacent the opening 2, shown in dotted lines in Figure 2 of the drawings, surrounding the pole 3. The closure member consists of a plurality of strips 4, which extend transversely and are secured to each other in any suitable manner to form a flexible curtain. The edges of these curtains or closure members are received in suitable guides 5 and the closure members are mounted on suitable rolls arranged in casings 6 at each end of the guides. The rolls on which the curtains or closure members are mounted are of ordinary construction and are supported on stub shafts 7, journaled in the side walls 8 of the casings. As shown, the meeting edges of the closure members are recessed, as at 9, to fit around the pole when in closed position, and are further provided with cushioning members 10, formed of felt or similar material, which permit the meeting edges to snugly fit each other and also serve as means for absorbing any shock when the edges of the closure members come together.

The closure members are normally retained in closed position by means of springs 11, carried by stub shafts 7 (see Figure 8). As shown, each stub shaft is provided with a pair of spaced disks 12 at one end and a tape 13 extends from one shaft to the other between the disks. This tape passes over suitable idler rolls or pulleys 14. The tape is coiled around the shafts over the springs 11 and the ends secured to the springs, as at 15.

Within the casing there is provided a relay 16 which is adapted to be energized when an alarm is sounded and which controls the opening of the shutters. As shown (see Figure 3), the relay is arranged in a main

signal or alarm circuit 17, which is provided with a suitable source of current 18 and in which a switch 19 diagrammatically illustrates the usual fire alarm signal by means of which the circuit is closed when an alarm is sounded. The bell or buzzer 20 represents the signal arranged in the engine house. When a fire signal is sounded, the relay is energized, attracting a plate 21 arranged 10 within the casing and connected to a pivoted arm 22 (see Figure 10). This arm is revolved in a clockwise direction by the energizing of the relay and is adapted to swing a trip member 23 on its 15 pivot. The trip member is normally retained in operative position by means of a spring 24 and is pivotally mounted on a pin or shaft 25. A bracket 26 is arranged opposite the trip member and this bracket 20 is adapted to pivotally support an arm 27, which arm is provided with a flattened upper portion or face 28 (see Figures 4 and 11). A main trip lever 29 rests upon this flattened face 28 and extends from the casing 25 (see Figure 9). The lever is pivotally mounted on a pin 30, carried by a bracket 31 on the side of the casing and is provided with a yoke 32 on its outer end. Adjacent its inner end, the trip lever is connected to a 30 pair of springs 32, the lower ends of which are anchored in a plate 33 supported by a main shaft 34. The springs normally urge the trip lever to the dotted line position shown in Figure 9 of the drawings and 35 when the relay is energized, the lever is adapted to assume this position. A spring 35 is connected to the arm 27 and is adapted to return it to normal position.

A vertically disposed actuating member 36 40 is connected to the main trip lever. As shown, this member is provided with a pair of spaced flanges 37, adapted to receive the main trip lever and is secured thereto by means of a pin 38. The lower 45 end of the actuating member is provided with an enlargement 39 adapted to engage an arm 40 when it is depressed. This arm is provided with a finger or extension 42, adapted to be received in a notch or recess 43 in a switch actuating arm 44. The switch 50 actuating arm is carried by a sleeve 45, mounted on a shaft 46. The free end of the switch actuating arm is provided with a recess 47 and this end of the arm is received 55 between pins 48 mounted on a main switch lever 49. A switch casing 50 is arranged within the main casing and when the switch lever 49 is depressed, a movable contact 51 (see Figure 12) is adapted to be moved into 60 engagement with a pair of stationary contacts 52. As shown (see Figure 3), these stationary contacts are connected to a source of current 53 and to a motor 54 arranged within the casing and the motor is thus put 65 in operation when the relay is energized.

The motor shaft is provided with a pinion 55 and is connected by a train of gears 56 to the main shaft 34. Externally of the casing, the main shaft is provided with a gear 57 which is loosely mounted thereon and is provided with a hub or extension 58 carrying a disk 59. The arms of the yoke 32 are provided with spaced fingers 60 at their lower ends, which fingers receive the disk 59. Projecting from the face of the hub is a pin 61 and the shaft is also provided with a projecting pin 62. When the trip lever 29 swings to the dotted line position, the pins 61 and 62 are moved out of engagement with each other and the springs 15 70 open the shutter. As the trip lever is returned to normal position by the springs 32, the pin 61 is brought into alignment with the pin 62 and as the shaft revolves, the pinion 57 is revolved when these pins come in 75 contact with each other. The pinion 57 meshes with a pinion 63 carried by one of the stub shafts 7.

The trip lever 29 is adapted to be returned to normal position, against the tension of 80 springs 32 by means of a cam 64 mounted on the main shaft. As shown (see Figure 5), this cam is adapted to engage the enlargement 39 and raise the trip lever. In the meantime, the springs 24 and 35 have moved 85 the arm 27 and trip 23 to their normal position to lock the trip lever in raised position against the tension of the springs 32 and the trip member 22 is returned to its normal position by means of a spring 65. 90 When the enlargement 39 moves upwardly, the arm 40 which is secured thereto, also moves upwardly and this raises a pivoted lever 66 which is mounted in an arm 67 carried by the sleeve 45. This lever is provided with a lug 68 on its outer end adapted 95 to be engaged by a second cam 69 carried by the main shaft. When the cam 69 engages the lug 68, the lever 66 is moved longitudinally, revolving the sleeve 45 and the shaft 100 46 in a clockwise direction. This raises the switch lever 42 and the switch arm 49 to 105 open the motor circuit.

A pair of brake elements 70 are arranged 110 adjacent the motor shaft and carried by arms 71 pivotally mounted in a suitable supporting member 72. The lower ends of these arms are normally disposed adjacent each other and the brakes are adapted to 115 be actuated by spreading the arms. A brake 120 shaft 73 extends between the two arms and is provided with a cam 74. An arm 75 extends from this shaft and is connected to a link or lever 76. The outer end of this lever is provided with a slot 77 adapted 125 to receive a pin or shaft 78. This pin is carried by the pivoted lever 66 and when the lever 66 is moved longitudinally, the lever 76 is also adapted to move and revolve the brake shaft through the crank 130

connection formed by the arm 75. The lever 66 extends beyond its pivotal support in the arm 67 and is connected to a spring 79 which is adapted to return it to normal position.

Suitable means are provided for limiting the opening movement of the closure members or screen. As shown, a bracket 80 is secured to the outer edge of each closure member, and an arm 81 is connected thereto. The opposite ends of these arms are pivotally mounted in recesses 82 formed in the guides 5. The rear edge of this recess is inclined, as at 83, at the proper angle to limit the swing of the arm 81 and thus limit the opening movement of the shutter or closure member. Springs 84 are connected to the arms adjacent their pivots and the opposite ends of these springs are connected to the guides to normally return the arms to their proper position.

The operation of the device will be apparent from the foregoing description. When a signal is given over the circuit 25 17, the relay 16 is energized, attracting the plate or bar 21 which, in the manner described, releases the main trip lever 29. When the main trip lever is released, the gear 57 is moved longitudinally of the main 30 shaft 34 to a point where the outer end of the pin 61 is beyond the plane of the pin 62. This releases the restraining means on the shutters and the springs 15 which are under tension, open the shutters. The 35 tape 13 causes the shutters to move in unison and the arms 81 limit the movement of the shutters. The shutters are adapted to remain in open position for a predetermined length of time, controlled by the revolution of the shaft 34 and the position of the pinion 57. When the main trip lever 29 lowers, the actuating member 36 and arm 40 lower the switch lever 44 to close the motor switch and start the motor. When 40 the motor is started, the main shaft revolves and during the first portion of its revolution, the gear 57 is idle during which period of time the firemen are supposed to use the pole for the purpose of passing to 45 the lower floor. The revolution of the shaft 34 at a slow rate of speed through the train of gears 56 permits sufficient time for this purpose. As the shaft revolves, the cam 64 raises the trip lever 29 to its original position, which brings the pin 61 into operative 50 position, with respect to the pin 62 and the gear 57 is then revolved. The revolution of the gear 57 drives the gear 63 to close one shutter and the movement of the 55 tape 13 onto this shaft unwinds the tape from the other shaft and closes the other shutter at the same time.

After the cam 64 has performed its function by raising the main trip lever to its 60 original position and the trip mechanism

has assumed its original position, to lock the trip lever in raised position against the tension of springs 32 through the medium of springs 24, 25, and 65, the cam 69 functions to stop the motor. As stated, this 70 cam moves the lever 66 longitudinally which swings the switch lever 44 on its pivot to raise the outer end of the switch lever, and thus raise the switch member 49 to open the switch. At the same time, the brake 75 shaft is revolved to move the cam 74 substantially a half revolution and apply the brakes to the motor shaft. The parts are thus automatically returned to their original 80 position with the shutters in closed position and the mechanism ready to actuate upon the sounding of another alarm.

The motor circuit may be employed for lighting a number of lamps arranged throughout the engine house for the period 85 of time that the motor is in operation. As shown (see Figure 3), one contact 52 is connected to the motor by a lead wire 85 and the opposite pole of the motor is connected to the source of current by a lead 90 wire 86. The other contact is connected to the source of current by a lead wire 87. The lamps 88 diametrically illustrated in Figure 3 of the drawings, may be arranged at any desired points throughout the engine 95 house, and are shunted across the motor circuit. As shown, these lamps are arranged in series with each other, and are connected to the wires 85 and 86 by a lead wire 89. A switch 90 may be arranged in this wire 100 to permit operation of the motor and the closure member without lighting the lamps. When the switch is closed, the lamps will be lighted whenever the motor is energized and will be extinguished when the motor is 105 cut off.

While the invention is shown applied to a closure member adapted to surround the opening adjacent the pole in a fire engine house, it is, of course, to be understood 110 that it may be applied to the opening of any type of closure member automatically when a given signal, such as a fire alarm, is sounded.

It is to be understood that the form of 115 my invention herewith shown and described is to be taken as a preferred example of the same, and that various changes in the shape, size, and arrangement of parts may be resorted to without departing from the spirit 120 of the invention or the scope of the subjoined claims.

I claim:

1. In a device of the character described, a closure member having a bias toward open position, a motor to close said member, connecting means between said member and said motor, said connecting means being normally locked against movement to retain said closure member in closed position, and com- 130

bined means for unlocking a portion of said connecting means to permit said closure member to open and for closing a circuit to said motor; said combined means being 5 operable by said motor for connecting said closure member to said motor after a predetermined length of time to close said closure member.

2. In a device of the character described, 10 a closure member having a bias toward open position, a motor to close said member, a shaft connected to said motor, driving means operatively connected to said closure member and mounted on said shaft and normally 15 restrained against movement whereby said closure member will be normally retained in closed position, combined means for moving a portion of said driving means longitudinally of said shaft to release said portion 20 of said driving means from restraint and permit said closure member to open and for starting said motor, and means for returning said portion of said driving means to its original position during the rotation 25 of the shaft by said motor to close said closure member.

3. In a device of the character described, 30 a closure member, a shaft controlling said member, a pinion mounted on said shaft, a main shaft, a gear loosely mounted on said main shaft and operatively connected to 35 said pinion, a normally engaged clutch connecting said gear to said main shaft to retain said closure member in closed position, electrically controlled means for releasing 40 said clutch to permit said closure member to open, a motor for revolving said main shaft, and means for reengaging said clutch while said shaft is revolving to cause said closure member to return to its original position.

4. In a device of the character described, 45 a closure member having a bias toward open position, a main shaft, rotating means for said shaft, a gear loosely mounted on said main shaft and operatively connected to 50 said closure member, a normally engaged clutch connecting said gear to said main shaft to retain said closure member in closed position, a trip member connected to said clutch to disengage it, means controlled by the actuation of said trip member for start-

ing the rotating means for said shaft, means for returning said trip member to normal position whereby said clutch will be reengaged and said closure member returned to closed position, and means for stopping the rotating means when the closure member is returned to closed position.

5. A device constructed in accordance with 60 claim 4 wherein a brake is provided operated by the rotation of said main shaft to stop said shaft after a predetermined period of rotation.

6. A device constructed in accordance with 65 claim 4 wherein actuation of said trip member is controlled by a relay.

7. In a device of the character described, 70 a closure member having a bias toward open position, a main shaft, a gear loosely mounted on said main shaft and operatively connected to said closure member, a clutch connecting said gear to said main shaft and normally engaged to retain said closure member in closed position, a trip lever connected to said clutch and adapted to disengage 75 said clutch when actuated, electrically controlled means for actuating said trip lever, an electric motor connected to said shaft, means controlled by the actuation of said trip lever for starting said motor, means for returning said trip lever to its original position, and means for stopping the motor when the closure member is closed.

8. A device constructed in accordance with 80 claim 7 wherein said motor is controlled by a switch adapted to be closed by the actuation of said trip lever.

9. A device constructed in accordance with 85 claim 7 wherein said starting means consists of a switch adapted to be closed by the actuation of said trip lever and said stopping means includes a cam on the main shaft 90 adapted to open said switch.

10. A device constructed in accordance 95 with claim 7 wherein said motor is provided with a brake and said main shaft is provided with a cam adapted to actuate said brake.

In testimony whereof, I affix my signature.

LEWIS R. TOMPKINS.
